CLAIM

The ornamental design for a caddy accessory, as shown and described.

DESCRIPTION

FIG. 1 is a top, front, left perspective view of a caddy accessory showing our new design;

FIG. 2 is a bottom, rear, right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent to the shaded area define the bounds of the claimed design and form no part thereof. The broken lines depicting the remainder of the caddy accessory form no part of the claimed design.

1 Claim, 7 Drawing Sheets
